UNITED STATES PATENT OFFICE

147,117

DESIGN FOR A FONT OF TYPE

Therrin J. Deckard, Joplin, Mo.

Application July 6, 1946, Serial No. 131,340

Term of patent 3½ years

(Cl. D64—12)

To all whom it may concern:

Be it known that I, Therrin J. Deckard, a citizen of the United States, residing in the city of Joplin, county of Jasper, and State of Missouri, have invented a new, original, and ornamental Design for a Font of Type, of which the following is a specification, reference being had to the accompanying drawing forming a part thereof.

The drawing illustrates face views of a font of type, showing my new design.

I claim:

The ornamental design for a font of type, substantially as shown.

THERRIN J. DECKARD.
